UNITED STATES PATENT OFFICE

149,524

DESIGN FOR A TABLE

Carl W. Sundberg, Detroit, Mich., assignor to Reynolds Metals Company, Richmond, Va., a corporation of Delaware

Application July 2, 1946, Serial No. 131,262

Term of patent 7 years

(Cl. D33—14)

To all whom it may concern:

Be it known that I, Carl W. Sundberg, a citizen of the United States, residing in Detroit, Michigan, have invented a new, original, and ornamental Design for a Table, of which the following is a specification, reference being had to the accompanying drawing, forming part thereof.

The drawing is a perspective view of a table showing my new design.

I claim:

The ornamental design for a table, as shown.
CARL W. SUNDBERG.
